US00D824882S

(12) **United States Design Patent** (10) **Patent No.:** **US D824,882 S**
Zheng et al. (45) **Date of Patent:** **** Aug. 7, 2018**

(54) **GIMBAL WITH HANDLE**(71) Applicant: **SZ DJI Osmo Technology Co., Ltd.**,
Shenzhen (CN)(72) Inventors: **Haibin Zheng**, Shenzhen (CN); **Min Kim**, Shenzhen (CN)(73) Assignee: **SZ DJI Osmo Technology Co., Ltd.**,
Shenzhen (CN)(**) Term: **15 Years**(21) Appl. No.: **29/618,610**(22) Filed: **Sep. 22, 2017****Related U.S. Application Data**

(63) Continuation of application No. 29/601,445, filed on Apr. 21, 2017, now Pat. No. Des. 799,447, which is a continuation of application No. 29/566,534, filed on May 31, 2016, now Pat. No. Des. 794,606.

(51) **LOC (11) Cl. .... 14-03**(52) **U.S. Cl.**USPC ..... **D14/217****(58) Field of Classification Search**USPC D14/217, 253, 251, 252, 447, 451, 452, D14/440, 434, 458, 432, 439, 453, 460, D14/238.1, 140, 142, 149, 148; D13/107, D13/108, 218; D16/200-208

Primary Examiner — Mitchell I. Siegel*Assistant Examiner* — Khawaja Anwar(74) *Attorney, Agent, or Firm* — Sterne, Kessler, Goldstein & Fox P.L.L.C.(57) **CLAIM**

The ornamental design for a gimbal with handle, as shown and described.

DESCRIPTION

FIG. 1 is a top front perspective view of a gimbal with handle showing the claimed design;

FIG. 2 is a top rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines in the figures show portions of the gimbal with handle that form no part of the claimed design.

1 Claim, 7 Drawing Sheets# US D824,882 S
